EDGE SEWING MACHINES

Heinrich Muller and Karl Schwalbach, Frankfurt am Main, Germany, assignors to Maschinenfabrik Moenus A. G., Frankfurt am Main, Germany, a firm

Application October 27, 1953, Serial No. 388,556

Claims priority, application Germany November 7, 1952

10 Claims. (Cl. 112—62)

This invention relates to edge sewing machines of the kind which is used for the sewing or closing of trunks, boxes, cases and the like along their edges and in which the work piece is guided over a horn in the machine past the sewing instrumentalities. In the present type of the machines of this kind the length of the horn has to be chosen to approximate the size of the boxes to be sewn, so that for operating on boxes of various sizes several machines are required. The length of the horn depended on the measurement of the boxes insofar, as with such sizes which did not correspond to the length of the horn, the ends or the sides of the boxes would strike against the horn or its support so that larger boxes could not be sewn. By holding the boxes in an inclined position this inconvenience could be alleviated but not removed.

The aforesaid disadvantage is largely due to the fact that in the machines as at present in use the horn is fixed in position and cannot, therefore, be turned away from the obstructing parts of the boxes to be sewn.

It is, therefore, the main object of the invention to provide an edge sewing machine of the aforesaid type in which the said disadvantages are absent and in which boxes and cases of any commercial sizes can be accommodated and sewn along the full length of all their edges on one and the same machine.

Another object of the invention is the provision of an edge sewing or bag closing machine of the aforesaid type in which the horn is revoluble so that it may be turned during the sewing operations out of the way of any obstructions which may be caused by parts of the work-piece under operation.

Turnable horns in sewing machines, especially shoe sewing machines, are known. In these machines, however, the horn merely serves for supporting a shoe inwardly in order to enable a thread being placed around the barb of the sewing needle by means of a rotary thread guide, or whirl, in the tip of the horn, whereas the sewing instrumentalities in these machines are positioned outside the horn tip and the needle penetrates the shoe sole from above. In edge sewing machines, in which boxes are fed over the horn, the turning of the latter has not been possible because in these machines the sewing instrumentalities, for example the sewing needle, the by-needle (which serves for covering up the barb of the sewing needle during its return stroke), and the needle guide are positioned within the horn tip in a definite arrangement which has to be maintained throughout the entire sewing operation.

It is, therefore, a further object of the invention, to provide an edge sewing or bag closing machine of the aforesaid type with means whereby the horn can be turned or swung around a central stem or pivot, so that the stitching or sewing instrumentalities within the horn will not be displaced but will always maintain their initial position irrespective of the angle through which the horn may have been turned.

Further objects and improvements of the invention will be apparent from the now following description of the

2

accompanying drawings, in which a preferred embodiment of the invention is illustrated by way of example, and in which:

Fig. 1 is a longitudinal section through the horn of an edge sewing machine in accordance with the invention.

Figs. 2 to 5 diagrammatically illustrate different positions of the horn and horn gear during the turning thereof.

Fig. 6 is a longitudinal section through the top of the horn on an enlarged scale.

The machine illustrated in Fig. 1 is of the type having a straight hooked needle and a straight feed awl. In the standard 1 of this machine is a bracket 2 in which the vertical bearing post 3 of the horn 4 is adapted to turn in ball bearings. The sewing instrumentalities, including 15 the straight needle 5, the by-needle and the needle guide, of which latter two only the tubular carriers 6 and 7 are visible in the section, and the work support or horn cap 8 with its sewing slot 9 are loosely journaled in the head portion 10 of the horn with their axes positioned coaxially with that of the turning post 3. For the purpose of the invention it is necessary that these vertically reciprocating parts should retain their positions as shown in the figure throughout the entire operation of the machine and in any angular position into which the horn may have been turned. To achieve this purpose the following arrangement has been provided:

Carried in the upright branch of the horn which constitutes a hollow vertical arm, is a vertical shaft 15 which penetrates with its ends through the top and bottom plates of the horn. Fixed to the upper end of the said shaft is 30 a sprocket or chain wheel 16, while another and preferably, but not necessarily, larger chain wheel 17 is fixed to the lower end of the said shaft. The upper chain wheel 16 is connected by means of a chain 18 to a chain wheel or sprocket 19 which forms part of a sleeve 20 to which the horn cap 8 is fixed as by screwing. A pin 21 which projects inwardly from the aforesaid sleeve 20 extends into a slot 22 of the needle bar 23 and prevents the turning of the sewing tools in a manner still to be described. 35 The lower chain wheel 17 is in connection, by means of the chain 24, with the chain wheel 25 which is screwed to the machine frame and thereby is prevented from rotating. The lower chain wheel 17 is in connection, by means of the chain 24, with the chain wheel 25 which is screwed to the machine frame and thereby is prevented from rotating.

If now, during the operation of the machine, the horn 4 is turned about its bearing post 3, the vertical shaft 15 is moved with the horn so as to describe a circle with the bearing post 3 as a centre. Since, however, in the further progress of the sewing operation, it is necessary that the shaft 15 should maintain its position shown in the drawing, its tendency to turn has to be counteracted, which is done in the following manner:

Since the chain wheel 25 does not turn because of its being screwed to the machine frame, the chain 24 does not have to transmit any driving action. However, owing to the change in the angular position of the line intersecting the wheels 25 and 17 during the turning of the horn, the links of the chain roll off on the teeth of the wheel 25, whereby the chain is caused to move gradually around the said two wheels. This movement may take place to the right or to the left according to the turning direction of the horn, and it counteracts the tendency of both the gear wheel 17 and, therewith, of the vertical shaft 15 to turn about their common axis. Thus the shaft 15, which is loosely journaled in the vertical horn arm, and the wheel 17 remain in the position shown in Fig. 1 during their whole travelling movement about the turning post 3, that is to say, they will always present the same side to the attendant standing in front of the machine.

Figs. 2 to 5 illustrate the procedure during the turning of the horn to the right. The position in Fig. 2 of the horn 4 at the beginning of the turning movement about the post 3 corresponds to that shown in Fig. 1. The

vertical shaft 15 is loosely journaled in the horn 4, but its free rotation is prevented by the chain wheel 17 at its lower end being held immovably by the chain 24 and the stationary chain wheel 25. In order better to be able to understand the rolling-off movement of the chain along the two chain wheels 25 and 17, dashes 1 to 8 have been drawn on both wheels which are intended to represent the teeth of the said wheels. The chain links starting from the point 1 of the wheel 25 have been designated A, B, C, D and those starting from the point 1 of the wheel 17 are denoted by a, b, c, d. It is to be understood, that both wheels must have the same ratio and that they are, therefore, of equal size and provided both with the same number of teeth.

In the position shown in Fig. 3 the horn 4 is assumed to have been turned through an angle of 135°. The screwed down wheel 25 has, of course, stayed in its position which is borne out by the tooth No. 1 having remained in its top position as shown in the figure, but the vertical arm 4 has, by virtue of its movement, changed the position of the chain links. Link A is still on tooth 1, but the other links B, C, D, which were free in Fig. 2, have placed themselves along the right side of the wheel 25 and are now in engagement with the teeth 2, 3 and 4 of the same. Hereby the chain links a, b, c, d have been retarded in relation to the chain wheel 17, or in other words, during the turning of the horn about its post 3 the chain wheel 17 has moved backward on the chain links using the chain as a track, and thereby has taken the chain with it, without thereby altering its position. Also in this case point 1 of the chain wheel 17 has maintained its position at the top of the wheel. Only the link d is still on tooth 4, while the links c, b, a are already on the free part of the chain. There has been, strictly speaking, a release of the links a, b and c from the teeth 1, 2 and 3 in a direction opposite to the direction of turning.

On turning the horn through another 180° into the position shown in Fig. 4 the chain 24 has continued its travel and the chain wheel 17 is now reapproaching its starting position which it will have attained by moving through a last 45° into the position of Fig. 5. The chain has travelled, in the example shown, by an amount of 12 links and since this travel, owing to the fixed position of the chain wheel 25, has been in the reverse direction to the turning of the horn, it has caused the shaft 15 during this turning movement through all angular positions of the horn to remain stationary relative to the remainder of the machine. This turning movement has been to the right; when turning the horn to the left, the chain will travel in the opposite direction.

The same procedure as the one just described takes place between the upper chain wheels 16, 19, and their connecting chain 18. Also in this case the ratio of the wheels 16 and 19 will have to be as 1:1, while the ratio of the two pairs of wheels, viz: 25, 17 and 16, 19 may be as desired.

During the turning of the horn under maintenance of the initial position of the shaft 15, the upper chain wheel 16 also maintains its initial position and it thus constitutes the fixed wheel in the sense of the aforescribed chain wheel 25 of the lower set. Similar to the lower gear the links of the chain 18 of the upper gear move over the teeth of the wheels 16 and 19 by the amount of a few links without thereby producing any driving action. This results in that the loosely turnable chain wheel 19 together with the horn cap 8 fastened thereto, is held in its initial position in spite of the turning of the horn and the chain travel. Thus, also in this case, the tendency of the chain wheel 19 and its connected parts to participate in the turning of the horn is being counteracted. Turning of the needle bar and its connected parts is prevented by the pin 21 taking into the slot 22 thereof, whereby it is to be remembered that the pin 21 is fixed to the sleeve-like extended hub of the wheel 19 and is held stationary together with the same. In this way and by the described

means all the sewing instrumentalities in the horn and the horn cap 8 with its slot 9 maintain their initial positions as shown in Fig. 1.

It is to be understood that the invention is not intended to be limited to the aforescribed means for maintaining the sewing instrumentalities and the horn cap in their initial positions, but that other means, such as intermediate gear wheels, toothed racks or the like may be provided in place of the chains 18 and 24. Instead of geared means other suitable connections, such as links and levers or the like may be arranged for the object of maintaining the initial positions of the aforesaid instrumentalities despite the turning of the horn for the purpose specified or for any other purpose, with the axes of the said instrumentalities remaining coaxial with the turning axis of the horn.

The up and down movement of the needle bar 23 and its associated instrumentalities also takes place without being impeded by the turning of the horn. For this purpose the following mechanism is provided:

A ball-ended tappet rod 30 is provided and is slidably arranged in the central bore of the bearing post 3 of the horn, of which rod the ball-shaped knuckle engages the one arm 31a of the two-arm lever 31. This lever is pivoted in the machine frame at 32, and its rearwardly extending arm 31 is connected to a similar double lever 33, 33a in the head of the horn by means of a connecting rod 34, which transmits the motion of the lever system just referred to to the upper lever system. The lever arm 33a serves for reciprocating the needle bar 23 by means of an interpositioned link 38.

A similar system is provided to reciprocate the by-needle and the guide needle also in vertical direction. This movement is initiated by a tubular tappet rod 40 which encloses the tappet rod 30, over the lower double lever 39, 39a and the connecting rod 50 to the upper double lever 36, 36a, and from there over the link 37 to the sleeve 35 on which the by-needle and the needle-guide are arranged. The movement of these parts is derived from the driving mechanism of the machine (not shown) over a rod 41, the bell crank levers 42, 43 and the links 44, 45, of which the former acts on the tappet rod 30 and the latter on the tubular tappet 40. The reference numeral 46 denotes the feed awl of the machine which is arranged outside of the horn over the horn cap 8 and which effects the feed of the work piece through the slot 9 provided therein.

What we claim is:

1. In an edge sewing machine having a horn and vertically reciprocable sewing instrumentalities including a straight needle operating through a slot in the top of the horn, a turning post for the horn coaxial with the axis of the straight sewing needle, a bearing in the machine frame for turnably supporting the said horn, and means intermediate the horn support and the sewing instrumentalities for counteracting the turning tendency of said sewing instrumentalities relative to the remainder of the machine during the turning movement of the horn about the said turning post.

2. In an edge sewing machine having a horn and vertically reciprocable sewing instrumentalities including a straight needle operating through a slot in the top of the horn, a turning post for the horn coaxial with the axis of the straight sewing needle, a bearing in the machine frame for turnably supporting the said horn, and geared means including a gear wheel stationary on the machine frame intermediate the horn support and the sewing instrumentalities for counteracting the turning tendency of said sewing instrumentalities relative to the remainder of the machine during the turning movement of the horn about the said turning post.

3. In an edge sewing machine having a horn and vertically reciprocable sewing instrumentalities including a straight needle operating through a slot in the top of the horn, a turning post for the horn coaxial with the axis of the straight sewing needle, a bearing in the

machine frame for turnably supporting the said horn, means intermediate the horn support and the said sewing instrumentalities for counteracting the turning tendency of said sewing instrumentalities relative to the remainder of the machine during the turning of the horn comprising a gear wheel stationary on the machine frame at the lower part of the horn and coaxial with the said turning post, a second gear wheel having a sleeve-like extended hub surrounding said sewing instrumentalities, a vertical shaft loosely journaled in the said horn at a distance from the said turning post, a third gear wheel fixed to the upper and a fourth gear wheel fixed to the lower end of the said vertical shaft, connecting means between the first and fourth gear wheels at the lower part of the horn, and connecting means between the second and third gear wheels at the upper part of the horn.

4. In an edge sewing machine having a horn and vertically reciprocable sewing instrumentalities including a straight needle operating through a slot in the top of the horn, a turning post for the horn coaxial with the axis of the straight sewing needle, a bearing in the machine frame for turnably supporting the said horn, means intermediate the horn support and the said sewing instrumentalities for counteracting the turning tendency of the said sewing instrumentalities relative to the remainder of the machine during the turning of the horn comprising a chain wheel stationary on the machine frame at the lower part of the horn and coaxial with the said turning post, a second chain wheel having a sleeve-like extended hub surrounding said sewing instrumentalities, a vertical shaft loosely journaled in the said horn at a distance from the said turning post, a third chain wheel fixed to the upper and a fourth chain wheel fixed at the lower end of the said vertical shaft, a chain connecting the first and fourth chain-wheels at the lower part of the horn, and a second chain connecting the second and third chain wheels at the upper part of the horn.

5. In an edge sewing machine having a vertical horn, a slotted horn cap serving as a work guide, vertically reciprocating sewing instrumentalities including a straight needle operating through the slot in said horn cap, a needle bar having a vertical slot in said needle bar, a bottom plate and a top plate for the said horn, a turning post at one end of said bottom plate coaxial with the axis of the straight sewing needle, a hollow vertical arm offset with respect to said turning post and connecting the said top and bottom plates, a vertical shaft loosely journaled in the said hollow arm and having chain wheels keyed to its upper and its lower ends, respectively, another chain wheel fixed to the machine frame and coaxially surrounding said turning post, a chain connecting said fixed chain wheel with said chain wheel on the lower end of said vertical shaft, a further chain wheel having an extended hub fixed relatively to, and surrounding said sewing instrumentalities at the upper part of the horn, a pin in said extended hub extending into the longitudinal slot in the needle bar to prevent turning of the said sewing instrumentalities, and a second chain connecting said further chain wheel with said chain wheel at the upper end of said vertical shaft.

6. In an edge sewing machine having a vertical horn and vertically reciprocable sewing instrumentalities including a straight needle in said horn, a slotted cap at the top of said horn, a longitudinally drilled turning post for the horn coaxial with the axis of said straight needle, a bearing in the machine frame for turnably supporting the said horn, a hollow vertical arm constituting the vertical member of the horn and arranged to swivel about said turning post, a vertical shaft loosely journaled in said hollow arm, a chain wheel keyed to the top of said vertical shaft, a second chain wheel keyed to the lower end of said shaft, a third chain wheel fixed

on the machine frame surrounding the said turning post, a fourth chain-wheel fixed relatively to said sewing instrumentalities, geared means connecting the chain wheels at the top and geared means connecting the chain wheels at the bottom of the horn, a solid and a hollow tappet vertically movable in the central drilled bore of said turning post, links in connection with the said sewing instrumentalities, other links in connection with the said solid and hollow tappets, means for raising and lowering said links and, connecting rods in said hollow arm to connect said links on the tappets with the said links on the sewing instrumentalities.

7. In an edge sewing machine, a vertical horn, a top and a bottom plate for said horn, a hollow vertical arm connecting said top and bottom plates at one end thereof, a turning post depending from the free end of the bottom plate, a central drilled bore in the said turning post, a vertical bearing in the machine frame for turnably supporting said turning post and horn, a lower chain wheel non-turnably fixed to the machine frame surrounding the said turning post, sewing instrumentalities including a straight needle and needle bar in the free end of the top plate, coaxially located with the axis of the said turning post, an upper chain wheel encircling the said sewing instrumentalities and loosely journaled in the said top plate, gearing means intermediate the said non-turnable lower chain wheel and the upper chain wheel for preventing rotary movement of said sewing instrumentalities, longitudinally movable driving means for the sewing instrumentalities in the bore of said turning post, means to reciprocate said driving means, and means in the vertical arm of the horn for transmitting the movements of the said driving means to the sewing instrumentalities.

8. In an edge sewing machine, a vertical horn, a top and a bottom plate extending horizontally from said horn, sewing instrumentalities including a straight needle and needle bar vertically reciprocable at the free end of said top plate, a centrally bored turning post depending from the lower part of the horn at the free end of said bottom plate coaxially with said needle and needle bar, a vertical bearing in the machine frame for supporting said turning post, a fixed gear wheel surrounding said turning post, geared means between the said gear wheel and the sewing instrumentalities for preventing rotation of said instrumentalities relative to the remainder of the machine during the turning of the horn, a link and lever arrangement to reciprocate said sewing instrumentalities, a hollow tappet passing through the bore in said turning post, a solid tappet passing through said hollow tappet, means to reciprocate said tappets from the driving parts of the machine, and means within the hollow arm of the horn for transmitting the reciprocating movement from the said tappets to the said link and lever arrangement of said sewing instrumentalities.

9. An edge sewing machine as set forth in claim 5, in which the cooperative chain wheels at the top of the horn and the cooperative chain wheels at the bottom of the horn are all of the same ratio.

10. An edge sewing machine as set forth in claim 5, in which the cooperative set of chain wheels at the top of the horn and the cooperative set of chain wheels at the bottom of the horn is of the ratio 1:1 in each set, while the ratio of either set with respect to the other is different.
